(57) **CLAIM**

The ornamental design for a flush ceiling fan shield, as shown and described.

DESCRIPTION

FIG. 1 is a bottom, right front axonometric view of a flush ceiling fan shield showing my new design in the environment of use.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a bottom plan view thereof.

FIG. 7 is a view identical to FIG. 1, but shown without the environment.

FIG. 8 is a top, right, rear axonometric view of the thereof.

FIG. 9 is a front elevational view thereof, the rear view being identical thereto.

FIG. 10 is a left side elevational view thereof.

FIG. 11 is a right side elevational view thereof.

FIG. 12 is a bottom plan view thereof; and,

FIG. 13 is a top plan view thereof.

The broken lines in the figures represent environmental structure and they form no part of the claimed design.
